UNITED STATES PATENT OFFICE.

LOUIS HAAS, OF NEW YORK, N. Y.

PIANO-PEDAL.

No. 873,742.

Specification of Letters Patent.

Patented Dec. 17, 1907.

Application filed April 17, 1907. Serial No. 363,635.

To all whom it may concern:

Be it known that I, LOUIS HAAS, a citizen of the United States, residing at the city, county, and State of New York, have invented certain new and useful Improvements in Piano-Pedals, of which the following is a full, clear, and exact description.

My invention relates to improvements in piano pedal construction.

10 Among the objects of the invention is to provide a simple, light, and yet strong and durable pedal construction.

In the accompanying drawings, Figure 1 is a side elevation. Fig. 2 is a longitudinal section. Fig. 3 is a view of the under side of Fig. 1, the forward end of the shank portion being broken away. Fig. 4 is a cross section on the plane of the line X—X Fig. 1, looking in the direction of the arrow. Fig. 5 is a perspective view of a detail slightly modified.

15 1 is the shank, which is that portion of the pedal which projects into the piano case, and is suitably mounted in any of the well known ways so that it may be tilted by the foot.

20 2 is the foot piece, the upper surface of which is of conventional form. The shank 1 and the foot piece 2 are formed independently and separately. The shank 1 is formed of channel iron, preferably of uniform cross section throughout. The foot piece 2 is formed of any desired metal, and is preferably formed by a stamping or drawing process, so that its under side is hollowed out, forming in effect a comparatively thin shell,

25 which, because of its curved contour throughout, possesses very great rigidity and strength.

30 3—3 are inward extensions or cheek pieces which lie in the same plane with the sides of the inner portion of the foot piece 2. These cheek pieces embrace the sides of the shank 1 and are suitably secured thereto for example by rivets 4—4. As will be seen, the cheek pieces serve to cover and protect and hide from view the shank where the pedal 45 enters the piano case, the opening in the piano case being directly behind the vertical front wall of the foot piece.

40 5 is a plate of a suitable outline to substantially fill the space at the front end of the foot piece, so as to cover and protect the

opening in the piano case, as best seen in Fig. 2. This guard-plate 5 serves to prevent mice from getting into the case, as might otherwise occur. In the preferable form this plate 5 is bent around the end of 55 the shank 1 and has an upward extension 5^a, serving to fill out the upwardly projecting horn portion of the foot piece 2, thereby preventing the accumulation of dust. This plate 5 may be secured to the shank 1 in any 60 desired manner, for example, by means of a rivet 6.

7 represents a portion of the piano case, and 7^a the opening therein through which the shank of the pedal passes.

65 The foot piece 2 may be made of any suitable metal, but preferably a metal which will partake of the desired finish, such as brass or nickel. By reason of the lightness of the member, the foot piece may be made of solid 70 brass or solid nickel without undue extravagance, in fact more economically than the ordinary construction.

What I claim is:

1. In a piano pedal, a shank member, a 75 separate foot-piece hollowed out at the under side, means of connection between said foot-piece and said shank member, a separate guard-plate, means for securing said plate in the hollowed-out portion of said foot-piece, 80 adjacent the connection between said foot-piece and shank, said guard-plate substantially closing the hollowed-out space where said pedal enters the piano case.

2. In a piano pedal, a shank member channelled on its under side, a separate foot piece recessed or hollowed out on its under side, cheek pieces projecting inwardly from said foot piece and embracing the shank member at opposite sides, and a guard-plate transversely located in the space at the inner end of the foot piece and extending substantially from the lower edge of the foot piece to the shank to protect the opening in the piano case through which the shank passes.

3. In a piano pedal, a shank, a foot piece hollowed out on its under side, said foot piece embracing the shank on opposite sides, means for securing together the foot piece and shank member, and a guard-plate de- 100

pending from the shank and protecting the passage in the piano case through which said shank extends.

4. In a piano pedal, a shank, a separate foot piece hollowed out at its under side, portions of said foot piece extending above and below the plane of the shank, said foot piece embracing the shank on opposite sides and

secured thereto, and a guard-plate extending above and below the shank and closing the inner end of the foot piece.

LOUIS HAAS.
